UNITED STATES PATENT OFFICE.

CHARLES J. VAN DEPOELE, OF LYNN, MASSACHUSETTS.

COMMUTATOR-BRUSH CARRIER FOR ELECTRIC MOTORS.

SPECIFICATION forming part of Letters Patent No. 396,314, dated January 15, 1889.

Application filed February 8, 1887. Renewed November 24, 1888. Serial No. 291,801. (No model.)

To all whom it may concern:

Be it known that I, CHARLES J. VAN DEPOELE, a citizen of the United States, residing at Lynn, in the county of Essex and State of Massachusetts, have invented certain new and useful Improvements in Commutator-Brush Carriers for Electric Motors, of which the following is a specification, reference being had therein to the accompanying drawings.

10 The present invention relates to a novel and improved construction and arrangement of the mechanism for holding and adjusting the commutator - brushes of an electro - dynamic motor upon and around the commutator thereof; and it consists in providing a duplicate set of brushes supported in a frame, the frame itself being movable radially upon its support, so as to bring the brushes to any desired position upon the periphery of the commutator, the two sets of brushes being so mounted that by a single movement of an auxiliary handle either pair of the two sets of brushes may be brought into actual contact and operative relation with the surface 15 of the commutator. The two sets of brushes control the forward or backward rotation of the armature of the motor, and are quickly brought into or thrown out of action, they being then radially adjusted upon the commutator to produce the desired effect.

The construction and arrangement of my improved commutator-brush-carrying frame will be hereinafter fully set forth.

In the accompanying drawings, Figure 1 is a vertical elevation, partly in section, showing my improved commutator-brush-carrying frame, looking from the direction of the armature. Fig. 2 is an elevation, partly in section. Fig. 3 is a top view on the line 3 3 of Fig. 2. Fig. 4 is a top view on the line 4 4 of Fig. 2. Fig. 5 is a sectional elevation on the line 5 5 of Fig. 4, and Fig. 6 is a sectional elevation showing one set of brushes in contact with the commutator and the operative relation of the parts.

Similar letters denote like parts throughout.

A is the armature-shaft, and B is the outer main bearing or journal therefor, upon any convenient portion of which (in this instance the inner end, b) is mounted a hand-lever, C, mounted rotatively thereon and held in posi-

tion by means of a washer, D, secured to the bearing B. A set-screw, D', is also provided, by means of which the hand-lever C can be locked in any desired position—that, for example, in which the motor produces the desired results or its movement retarded in a greater or less degree. The commutator E is shown in section in Fig. 6 and in dotted lines in Fig. 2.

To the lever C are secured in corresponding positions on opposite sides of the armature-shaft spindles e, which are thoroughly insulated from said hand-lever and rigidly secured thereto. Upon the inner ends of the spindles e are pivotally mounted the oscillating brush-carrying frames F G, the frame F being provided with two brushes, f f', which are fitted obliquely into the ends of the oscillating frames and held in position by set-screws H. A similar set of brushes, g g', is secured in the frame G, and when in their central positions the brushes project away from the surface of the commutator on both sides. The set-screws H may be provided with jam-nuts h. From the outer ends of the frames F and G extend binding-posts I J, both binding-posts I being of one polarity and the posts J of the opposite, the line-wires or working - conductors of one polarity being 75 connected to both of the posts I and those of the opposite polarity to both of the posts J.

To the extremities of the posts I are pivotally attached links K, preferably of insulating material; but they may be of metal 85 thoroughly insulated from the binding-posts, which links extend downward and connect in a similar manner with the binding-posts J, thereby so connecting the rocking frames F and G that they will move in exact accordance with each other, and when so moved the two opposing brushes f g, constituting a set, will be brought into contact with the surface of the commutator, and when moved in the opposite direction the opposite 90 set of brushes, f' g', previously out of contact, will now be brought upon the commutator and the brushes f g removed therefrom, thereby changing the positions of the poles of the armature and reversing the direction of its 100 rotation. A second handle, L, preferably of insulating material, is securely attached to

the upper one of the rocking brush-carrying frames F, and extends upward parallel with and about to the same height as the hand-lever C, being arranged for convenient coaction therewith. The lever C is provided with a quadrant or notched rack, M, the notches of which are engaged by a spring-latch, m, attached to the lever L, and by which it is secured in the desired position with respect to the hand-lever C. As the lever L is moved to the right or left with respect to the hand-lever C, the rocking brush-carrying frames F and G are similarly moved and one or other of the sets of brushes placed in communication with the commutator, thereby determining the positions of the respective poles of the armature and its direction of rotation. The handle L is then secured in position by the entrance of the spring-latch m into one or other of the notches in the quadrant M, which should be at such a point as will cause the commutator-brushes to be pressed against the commutator with the desired pressure. When in position, the speed of the motor and the quantity of current permitted to flow therethrough is regulated by moving the handle C, and with it the brushes, around the commutator, as is ordinarily done with a single pair of brushes.

Various modifications in the construction and arrangement of the parts may be made without in any way departing from the spirit of my invention, and I do not therefore limit myself to the exact details of construction and arrangement shown and described.

35 What I claim is—

1. In an electric motor, the combination, with a circumferentially-movable lever, insulated commutator-brush-carrying frames pivotally mounted with respect to said lever, insulated connections extending between the pivoted frames for moving both simultaneously, and a double set of commutator-brushes secured in said frames and adapted to be interchangeably brought into operative relation with the commutator-cylinder by the movement of either one of said frames, and to be moved about the commutator, as desired, by the movement of the hand-lever, substantially as described.
2. In an electric motor, the combination, with a circumferentially-movable lever, insulated commutator-brush-carrying frames pivotally mounted with respect to said lever, insulated connections extending between the

pivoted frames for moving both simultaneously, a double set of commutator-brushes secured in said frames, and an adjusting-lever connected to one of said frames and arranged to be adjustably secured with respect to the pivoted lever, whereby said brushes may be interchanged upon any desired portion of the commutator-cylinder, substantially as described.

3. In an electric motor, the combination, with a fixed support, of a commutator-brush-carrying hand-lever radially movable thereon, a pair of commutator-brush-carrying frames pivotally mounted upon said lever, a double set of commutator-brushes secured to each of said frames, and connections between said frames, whereby when one set of brushes is placed in contact with the commutator the other set is lifted therefrom, the brushes when set being movable around the commutator by means of the hand-lever, substantially as shown and described.

4. In an electric motor, the combination of the hand-lever C, radially movable upon the bearing B and around the armature-shaft, the pivoted commutator-brush-carrying frames F G, secured to said lever, links K, extending between the said pivoted frames, an auxiliary hand-lever, L, extending upward from the frame G and provided with a latch-spring arranged to engage the notches of a rack carried by the bar C, whereby when the handle L is moved to right or left of the bar C the brush-carrying frames will be rocked and the set of commutator-brushes controlling the desired direction of rotation be brought into operative position upon the commutator, substantially as shown and described.

5. In an electric motor, the combination of the lever C, pivoted upon one of the main bearings thereon and provided with the rack M, of the pivoted frames F G, secured to the lever C on opposite sides of said support, binding-posts I, extending from said frames, and links K, extending between the opposite sides of the binding-posts, and thereby mechanically connecting said frames, substantially as shown and described.

In testimony whereof I hereto affix my signature in presence of two witnesses.

CHARLES J. VAN DEPOELE.
